CAN CONVEYING MACHINE

Edwin C. Kraus and Maurice V. Douthitt,
Ortonville, Minn.

Application January 31, 1949, Serial No. 73,847

13 Claims. (Cl. 198—30)

1

Our present invention relates to improvements in can or other receptacle conveying means.

While this invention is intended for general use, it is especially well adapted for use in connection with our can unloading machines disclosed and broadly claimed in our pending application for patent for "Method and Machine for Unloading Cans," filed May 14, 1947, under Serial No. 748,132, and our application for patent for "Can Unloading Machine," filed January 31, 1949, under Serial Number 73,846.

The object of this invention is to provide a highly efficient machine for conveying cans in bulk upright positions, in sorting the same into a row or rows and thereafter turning the upright cans into horizontal or rolling positions.

While the invention is shown and will herein-after be described for use in handling either empty or filled cans, it is equally well adapted for handling other receptacles.

To the above end, generally stated, the invention consists of the novel devices and combination of devices hereinafter described and defined in the claims.

In the accompanying drawings, which illustrate the invention, like characters indicate like parts throughout the several views.

Referring to the drawings:

Figs. 1 and 1^a are plan views of the improved can conveying machine segregated on the line $x-x$;

Figs. 2 and 2^a are right side elevational views segregated on the line $y-y$;

Fig. 3 is a view partly in side elevation and partly in longitudinal vertical section taken on the line 3—3 of Fig. 1^a;

Fig. 4 is a view partly in elevation and partly in section taken on the line 4—4 of Fig. 3, on an enlarged scale;

Fig. 5 is a detail view partly in elevation and partly in section taken on the line 5—5 of Fig. 3, on the same scale as Fig. 4;

Fig. 6 is a view principally in rear elevation with some parts sectioned on the line 6—6 of Fig. 2; on the same scale as Fig. 4;

Fig. 7 is a fragmentary detail view partly in plan and partly in section taken on the line 7—7 of Fig. 6;

Figs. 8 and 9 are fragmentary detail views partly in side elevation and partly in section taken, respectively, on the lines 8—8 and 9—9 of Fig. 1, on the same scale as Fig. 4; and

Fig. 10 is a fragmentary plan view with hanger arm sectioned on the line 10—10 of Fig. 9.

The numeral 11 indicates a long narrow skel-

2

eton frame having a pair of front legs 12 and a rear pair of legs 13 in the form of angle bars having on their lower ends leveling screws 14. The legs 12 and 13, on each side of the frame 11, are connected, at their upper ends by a side guide rail 15 comprising a rear section 16 and a front section 17 that is considerably shorter than said rear section and outwardly offset therefrom. The adjacent end portions of the guard rail sections 16 and 17 are rigidly connected by bending the forward end portion of the rear guard rail section 16 outwardly at right angles and rigidly securing the same to the front guard rail section 17 to afford a spacer 18. The 15 end of the front guard rail 17, at the spacer 18, is bent obliquely inwardly to the outer side of rear guard rail section 16 and rigidly secured thereto as a brace 19. It will be noted that the front guard rail section 17 is considerably higher than the rear guard rail section 16. The legs 12 and 13 at each side of the frame 11 are further connected at their intermediate portions by an angle bar 20 and braces 21.

Each side guard rail 15 is provided with an 25 adjustable section 22 that overlaps the front end portion of the rear guard rail section 16 on its inner side and secured thereto by a pair of screws 23. These screws 23 extend through longitudinal slots in the rear guard rail section 16 and have threaded engagement with the adjustable guard rail section 22. The forward end portion of the adjustable guard rail section 22 extends obliquely to the front guard rail section 17. The rear guard rail sections 16 have in-turned flanges 25 and a deck 26 in the plane of said flanges and secured thereto.

A wide endless conveyor belt 27 runs over a driven front roll 28 and a rear idle roll 29. The upper run of the belt 27 is supported on the flanges 25 and the deck 26 and its longitudinal edges are closely positioned to the rear guard rail sections 16. The driven roll 28 has a shaft 30 journaled in bearings 31 on horizontal angle bars 32 between the front guard rail sections 17 and the angle bars 20. These angle bars 32, at their front ends, are secured to the front legs 12 and their rear end portions extend obliquely upwardly and rearwardly and are secured to the flanges 25. The idle roll 29 has a shaft 33 journaled in bearings 34 slidably mounted in plates 35 secured to the rear pair of legs 13 and project rearwardly therefrom. Belt-tightening screws 36 have threaded engagement with the rear pair of legs 13 and impinge the bearings 34. The bearings 34 are connected by a cross-tie bar

37 having an upright member 38 provided with an inturned flange that affords a narrow deck 39 in the plane of the upper run of the belt 27.

On each side of the belt 27, at its forward end portion, is a narrow endless conveyor belt 40 that extends forwardly thereof. The two belts 40 run over pulleys 41 on a front driven shaft 42 and pulleys 43 on an idle shaft 44. The front shaft 42 is journaled in bearings 45 on the front pair of legs 12 and the idle shaft 44 is journaled in bearings 46 on the angle bars 32. The upper runs of the belts 27 and 40 are in the same plane.

Overlying the adjacent longitudinal edge portions of the belts 27 and 40 is a pair of inner guard rails 47, each in the form of a shallow channel, the flanges of which extend horizontally outwardly. The webs of the guard rails 47, at their inner end portions, are extended rearwardly of the flanges of said rails and are curved inwardly, as indicated at 48. A wide inverted channel bar 49 extends transversely over the belt 27 and also over the belts 40 forwardly of the adjustable guard rail sections 22. The channel bar 49, at each end portion, is supported on the transverse portions of a pair of yoke-like rods that afford a bearing 50. The transverse portions of the bearings 50 extend through aligned holes in the flanges of the channel bar 49. The legs of the bearings 50 are held for vertical adjustment in clamps 51 on the outer sides of the front guard rails 17. The bearings 50 are raised or lowered by long screws 52 having threaded engagement with short pieces of angle bars 53 on the outer sides of the front guard rail sections 17 between the members of each pair of clamps 51. The transverse portions of the bearings 50 loosely rest on the heads of the screws 52.

On the front flange of the channel bar 49 is a pair of angle members 54, each having a depending hanger arm 55. The guard rails 47, at their rear end portions, are attached to the hanger arms 55 by screw-threaded studs 56 on the webs of said guard rails. These studs 56 extend through holes in the webs of the guard rails 47 and said guard rails held where laterally adjusted on said studs, by pairs of opposing nuts 57. The guard rails 47, at their front end portions, are supported from upstanding ears 58 by studs 59 similar to the studs 56. These studs 59 extend through vertical slots 60 in the ears 58 and are secured to said ears by pairs of opposing nuts 61 on said studs. The ears 58 are secured to a cross-tie bar 62 that connects the two front legs 12. Integral with the ears 58 is a pair of forwardly projecting bearing plates 63. The cross-tie bar 62 also affords a support for the belts 40.

As heretofore stated, this invention is especially well adapted for use in connection with our can unloading machine and a fragment thereof is shown in Fig. 2, wherein the frame, the lift platform and the carriage are designated by the numerals 64, 65, and 66, respectively. Supported on the lift platform 65, within the carriage 66, is a plurality of tiers of cans x , the upper tier being partly moved over the deck 39 and onto the upper run of the belt 27. The bulk cans x on the belt 27, upon reaching the outer end portion of the machine, are divided at the transverse center of the belt 27, into two groups and deflected onto the belts 40 by the following mechanism, to wit: A pair of V belts 67 that deflect one group of cans x onto the right-hand belt 40 and a second pair of V belts 68 direct the other group of cans x onto the left-hand belt 40. These belts 67 and 68 all move in parallel horizontal planes. The belts 67 run over a pair of front pulleys 69 75

on a driven upright shaft 70 and a pair of rear eccentric pulleys 71 loose on an upright fixed shaft 72. The belts 68 run over a pair of front pulleys 73 on an upright driven shaft 74 and a pair of eccentric pulleys 75 loose on the fixed shaft 72.

The pairs of belts 67 and 68 are in forwardly diverging relation from the shaft 72 which is located at the transverse center of the belt 27 and the pairs of belts 67 and 68 where they pass around the pulleys 69 and 73 slightly overlying the inner longitudinal edge portions of the belts 40. The shafts 70 and 74, at their upper end portions, extend upwardly through holes in the web of the channel bar 49 and are journaled in bearings 76 within said channel bar and secured thereto. The fixed shaft 72 at its upper end portion is secured in the web of a short inverted channel bar 77 rigidly secured to the rear flange of the channel bar 49 at its longitudinal center and projects rearwardly therefrom.

The V-shaped space formed by the inner runs of the belts 67 and 68 is substantially filled with a V-shaped structure 78 held suspended from the channel bar 49. On the bottom of the structure 78 is a flat plate 79 that extends outwardly of the side thereof. The shafts 70 and 74, at their lower end portions, are journaled in the plate 79 and the fixed shaft 72, at its lower end, is secured in said plate.

The roll 28, the pulleys 41 and the shafts 70 and 74 are driven from an electric motor 80 mounted on the angle bars 20 at the front end portion of the frame 11. An electric cable 81 leads to a switch box 82 and a cable 83 leads to the motor 80. A flexible coupling 84 connects the armature shaft 85 of the motor 80 to a shaft 86 that extends into a variable speed unit 87 on the angle bars 20. A shaft 88 journaled in the housing of the variable speed unit 87 has on one of its end portions a large spur gear 89 that meshes with a spur gear 90 on a countershaft 91 journaled in bearings 92 on upright angle bars 93 secured to the angle bars 20 and 32. For the purpose of this case, it is not thought necessary to show the connections in the variable speed unit 87 from the shaft 86 to the shaft 88 for the reason that the same is so well known. A sprocket chain 94 runs over a sprocket wheel 95 on the countershaft 91, a sprocket wheel 96 on the shaft 42 of the roll 41, a sprocket wheel 97 on a transverse shaft 98 overlying the channel bar 49 and under a chain-tightening pulley 99 adjustably mounted on the right-hand angle bar 32. The shaft 98 is journaled in bearings 100 on the channel bar 49 and has secured thereto a pair of worm gears 101 that mesh with worm gears 102, on the shafts 70 and 74. The shaft 38 of the roll 28 is driven from the countershaft 91 by a sprocket chain 103 on the left-hand side of the machine, that runs over a sprocket wheel 104 on the countershaft 91 and a sprocket wheel 105 on the shaft 38.

From the above description, it is evident that the V belts 67 and 68 may be vertically adjusted, the guard rail section 22 may be endwise adjusted and the guard rails 47 may be vertically and laterally adjusted to accommodate the machine to cans of different sizes. The pair of V belts 67 and 68 deflect the cans x on the belt 27 onto the belts 40 into single rows and longitudinally spaced apart. The eccentric pulleys 71 and 73, acting on the V belts 67 and 68, facilitate the deflecting and feeding of the cans x from the belt 27 onto the belts 40. A bow-like guard rod

106, attached at its ends to the rear flange of the channel bar 49, overlies the cans *x* adjacent to the belts 67 and 68 and prevents said cans *x* from being forced upwardly over said belts by the crowding of the cans *x*.

The upright cans *x* in rows on the belts 40 are discharged from the right-hand belt 40 into a spiral chute 107 and from the left-hand belt 40 into a spiral chute 108 that is materially longer than the chute 107. Each chute 107-108 includes a plurality of half round rods 109 and 110, respectively. The rods 109, at their end portions, extend into front and rear upright square frames 111 and secured to the four sides thereof. The chute 108 includes front, rear and intermediate square frames 112 through which the rods 110 extend and are secured to the four sides thereof. The upright cans *x* discharged into the chutes 107 and 108 are turned thereby into horizontal rolling positions.

The rearmost frames 111 and 112 are pivotally secured to the front end portions of the bearing plates 63 and the guard rail section 17 by short links 113. Cans *x* are discharged from the chute 107 into an inclined trough 114 comprising an inner section 115 and an outer section 116. The outer trough section 116 comprises a pair of angle bars 117 cross-connected by the tie-bars 118. The delivery end portion of the chute 108 overlies the rear end portion of the trough section 116 and is spaced thereabove to permit the rolling cans *x* in the trough 114 to pass thereunder. Cans *x* in the chute 108 are discharged into the underlying trough section 116. The sides of the trough section 116, forwardly of the delivery end portion of the chute 108, are provided with up-standing side extensions 119 that, at their rear, extend to the top of the chute 108. The chute 108, at its delivery end, is supported on the side extensions 119. Cans *x* discharged from the chute 108 are directed into the trough section 115 by a pair of coiled springs 120 at the inner sides of the side extensions 119. Said springs 120 are forwardly and downwardly inclined and also prevent cans *x* in the trough section 116 from riding on the cans *x* on the bottom of said trough section. On the bottom of the trough 114 is a pair of track rails 122 in the form of half round rods on which the cans *x* roll.

The drawings illustrate a commercial form of the invention, but it will be understood that the same is capable of certain modifications as to details of construction, arrangement and combination of parts within the scope of the invention herein disclosed.

What we claim is:

1. In a machine of the class described, a main conveyor belt, a secondary conveyor belt at one side of said main belt, a belt extending transversely over the main belt for deflecting articles on the main belt onto the secondary belt, a pair of spaced pulleys over which the transversely extending belt is trained, and means for vibrating the transversely extending belt by bodily shifting the belt at the region of contact with one of said pulleys.

2. In a machine of the class described, a main conveyor belt, a secondary conveyor at one side of the main conveyor belt, a belt extending transversely over the main belt for deflecting articles on the main belt onto the secondary conveyor, means for driving the transverse belt, and a pair of spaced pulleys including an eccentric pulley over which the transverse belt runs.

3. In a machine of the class described, a main

conveyor belt, a secondary conveyor belt at each side of the main belt, a driven pulley at each side of the main belt, an idle eccentric pulley at the transverse center of the main belt, a deflecting belt arranged to run over each driven pulley and the eccentric pulley for deflecting articles on the main belt onto the secondary belts.

4. A machine as defined in claim 2, wherein said secondary conveyor comprises an endless belt, the conveyor surface of which is disposed substantially coplanar with the conveyor surface of the main conveyor belt.

5. A machine as defined in claim 2, wherein said secondary conveyor comprises an endless belt, the conveyor surface of which is disposed substantially coplanar with the conveyor surface of the main conveyor belt, the secondary conveyor belt being operable at a higher lineal speed than the lineal speed of the main conveyor belt.

20 6. A machine as defined in claim 2, wherein said eccentric pulley is disposed at the end of the transverse belt initially engaged by the articles moving along the main conveyor belt.

7. In a machine of the class described, a main conveyor belt, a secondary conveyor at each side of the main belt, a pair of pulleys respectively adjacent the sides of the main belt, a pair of eccentric pulleys overlying the main belt and more centrally disposed thereon in relation to the side pulleys, a deflecting belt arranged to run over each side and eccentric pulley, said deflecting belts being operable to deflect articles from the main belt onto the secondary conveyors, and means for driving the deflecting belts.

8. A machine as defined in claim 7, wherein said secondary conveyors comprise endless belts, the conveyor surfaces of which are substantially coplanar with the conveyor surface of the main conveyor belt.

40 9. A machine as defined in claim 7, wherein said secondary conveyors comprise endless belts, the conveyor surfaces of which are substantially coplanar with the conveyor surface of the main conveyor belt, the lineal speed of the secondary conveyor belts being greater than the lineal speed of the main conveyor belt.

10. A machine as defined in claim 7, wherein said eccentric pulleys are disposed in position for initial engagement by the articles conveyed upon the main conveyor belt.

50 11. A machine as defined in claim 7, wherein said eccentric pulleys are substantially coaxially mounted.

12. A machine as defined in claim 7, wherein said eccentric pulleys are substantially coaxially mounted at the transverse center of the main conveyor belt.

55 13. A machine as defined in claim 7, wherein each deflecting belt comprises upper and lower sections disposed substantially in vertical superimposition, and wherein the upper section of one belt lies in a plane between the upper and lower sections of the other belt.
